UNITED STATES PATENT OFFICE.

MICHAEL DERRECH, OF CLEVELAND, OHIO.

RAILROAD-SWITCH.

1,252,788.

Specification of Letters Patent.

Patented Jan. 8, 1918.

Application filed September 2, 1916. Serial No. 118,222.

To all whom it may concern:

Be it known that I, MICHAEL DERRECH, a subject of the Emperor of Austria, and a resident of Cleveland, in the county of 5 Cuyahoga and State of Ohio, have invented new and useful Improvements in Railroad-Switches, of which the following is a specification.

This invention relates to improvements in 10 switch throwing devices as applied to railway track construction, and has as its principal object the provision of means whereby an advancing train may automatically move a switch point so as to shift the train from 15 one track to a branch if desired.

A further object is to provide means which automatically hold the switch points in their adjusted position against accidental displacement.

20 These and other objects, such as simplicity of construction and operation, are attained by the novel design, construction and combination of parts hereafter described and shown in the accompanying drawing, forming 25 a material part of this disclosure, and in which:—

Figure 1 is a plan view showing a section of railroad track and indicating the application 30 of the invention.

Fig. 2 is a side elevational view of a locomotive having the operative mechanism attached at its front end, and

Fig. 3 is a plan view of a railway track showing the location of the switch points 35 after they have been moved.

It is a well known fact that the majority of accidents occurring on railways are caused by the misplacement of switches and particularly this is when the operation of the 40 switches is dependent upon the fallability of attendants.

In order to overcome such source of danger the automatically operating device herein indicated is provided.

45 Pivotedly secured to the ties of the road bed are a pair of links 10 and 11, arranged respectively adjacent to the inner track and branch rails, the links connecting with bell-crank levers 12 and 13 pivoted at 14 or 15 upon other ties or sleepers, the other end of the bell-crank levers engaging with bars 16 and 17, which extend past the switch point, the front end of the bars engaging with still other bell-crank levers 18 and 19, piv-

oted at 20 and 21 and having their front ends 55 engaged with other links 22 and 23, pivoted in ties in advance of the switch point.

Engaged with the bars 16 and 17, closely adjacent to the switch points, is a T shaped element 25 the oppositely extending ends of 60 which are pivoted to the bars while the front extending portion 26 is pivoted to a cross bar 28 pivoted at its end to the movable points 30 and 31 of the switch. An extension 33 of the cross bar 28 projects laterally 65 outward beyond one of the running rails and has pivotally engaged with it a lever 35 fulcrumed on the pivot 36 and formed with an angular V shaped point 34 at its extreme front end, the point and main portion of the 70 element 34—35 being raised to a height substantially coincident with the top of the running rails.

From the foregoing description and drawings it will be obvious that if the lever 75 34—35 be moved upon the fulcrum 36 a corresponding movement must ensue with respect to the switch points 30 and 31, so that they will be moved from one of the main track rails to the other thereby diverting the 80 train to the through or branch track as may be desired.

In order to accomplish the movement of the switch lever, a pair of pendant levers 40 are pivoted at 41 to a bracket 42 extending 85 rigidly in advance of the locomotive the other ends 43 of the levers being pivotally engaged with links 44 having connections 45 with operative handles 46 located within the 90 cab of the locomotive.

Thus it is possible for the engineer by operating the handles 46 to extend the levers 40 downward in such manner as to intersect and engage with the lever 34—35 upon either side, thereby actuating the switch point or if it is desired to use the track in a condition in which the switch is at that time set the levers 40 may be turned upward into the position shown by the dotted lines permitting the locomotive to pass without making 100 contact with the switch lever 34—35.

Having thus described my invention, what I claim as new and desire to secure by Letters Patent, is:—

In a railway track switch, the combination 105 with a pair of running rails, a branch track leading therefrom, switch tongues engaged with said running and branch rails,

connections between said switch tongues, a T shaped element pivotally engaged with said connections, bars pivotally engaged with said T shaped element, pairs of bell-crank levers engaged with the ends of said bars whereby they may be held in an adjusted position, a raised lever having its one end

engaged with said T shaped element, and means carried on a locomotive contactable with said raised lever whereby it may be thrown in either direction.

In testimony whereof I have signed my name to this specification.

MICHAEL DERRECH.
